(57) **CLAIM**

I claim the ornamental design for a connector and flange fitting for a water heater pan, as shown and described.

DESCRIPTION

FIG. 1 is a front perspective view of the connector and flange fitting for a water heater pan comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective shown in a position of use with environment; and,

FIG. 9 is an exploded perspective view.

The broken lines depict environment and form no part of the claimed design.

1 Claim, 9 Drawing Sheets
